UNITED STATES PATENT OFFICE

152,673

DESIGN FOR A CRUISE BOARD

Charles H. Clark, Mill Valley, Calif., assignor, by decree of court and assignments, of one-half to Julia D. Clark and one-half to Paul F. Schumacher, San Francisco, Calif.

Application May 9, 1947, Serial No. 138,944

Term of patent 14 years

(Cl. D71—1)

To all whom it may concern:

Be it known that I, Charles H. Clark, a citizen of the United States and resident of Mill Valley, in the county of Marin, State of California, have invented a new, original, and ornamental Design for Cruise Board, of which the following is a specification, reference being had to the accompanying drawing, forming part thereof.

Figure 1 is a top plan view of a cruise board, showing my new design.

Figure 2 is a side elevational view of the cruise board shown in Fig. 1.

Figure 3 is a front elevational view of the cruise board shown in Fig. 1.

Figure 4 is rear elevational view of the cruise

board looking at the opposite side from that shown in Fig. 3.

I claim:

The ornamental design for a cruise board, as shown.

CHARLES H. CLARK.
